(57) CLAIM

I claim the ornamental design for a skin care device with camera, as shown and described.

DESCRIPTION

FIG. 1 is a front, right side perspective view of a skin care device with camera embodying our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, right side exploded perspective view
thereof.

The broken lines shown in the figures represent portions of the skin care device with camera that form no part of the claimed design.
